US00D496340S1

(12) **United States Design Patent** (10) Patent No.: **US D496,340 S**
Zoeller et al. (45) Date of Patent: **** Sep. 21, 2004**

(54) **PANEL FOR AN ELECTROLYZER**

(75) Inventors: **Maria Zoeller**, Manchester, CT (US);
Robert Byron, Lebanon, CT (US)

(73) Assignee: **Proton Energy Systems, Inc.**,
Wallingford, CT (US)

(**) Term: **14 Years**

(21) Appl. No.: **29/178,315**

(22) Filed: **Mar. 25, 2003**

(51) LOC (7) Cl. **13-03**

(52) U.S. Cl. **D13/184**

(57) **CLAIM**

The ornamental design for a panel for an electrolyzer, as shown and described.

DESCRIPTION

FIG. 1 is a front perspective view of a panel for an electrolyzer, showing our new design, and an enclosure for an electrolyzer shown throughout the FIGURES in broken lines for illustrative purposes only and forming no part of the claimed design;

FIG. 2 is a first side view thereof;

FIG. 3 is a front view thereof;

FIG. 4 is a second side view thereof;

FIG. 5 is a back view thereof;

FIG. 6 is a top view thereof; and,

FIG. 7 is a bottom view thereof.
